(57) **CLAIM**

The design for a vacuum insulated bowl with lid, as shown and described.

DESCRIPTION

FIG. 1 is an isometric view of the claimed vacuum insulated bowl with lid, embodying the present design;

FIG. 2 is a front view thereof;

FIG. 3 is a rear view thereof;

FIG. 4 is a right side view thereof;

FIG. 5 is a left side view thereof;

FIG. 6 is a top down plan view thereof; and,

FIG. 7 is a bottom up plan view thereof.

The stippling in the drawings represents texture and forms no part of the claimed design.
